UNITED STATES PATENT OFFICE.

WILLIAM J. EICHER, OF SMITHTON, PENNSYLVANIA.

FROG FOR SWITCHES.

No. 828,725.

Specification of Letters Patent.

Patented Aug. 14, 1906.

Application filed March 30, 1906. Serial No. 308,963.

To all whom it may concern:

Be it known that I, WILLIAM J. EICHER, a citizen of the United States of America, residing at Smithton, in the county of Westmoreland and State of Pennsylvania, have invented certain new and useful Improvements in Frogs for Switches, of which the following is a specification, reference being had therein to the accompanying drawings.

10 This invention relates to certain new and useful improvements in railway construction; and the invention relates more particularly to the frogs or crossovers used in connection with the tracks of a railroad where the rails 15 of a track intersect.

The primary object of my invention is the provision of novel means, in connection with a frog, for preventing the flanged wheels of the rolling-stock from becoming displaced 20 when passing over the frog. To this end I have devised an auxiliary flange or rib which is carried by a frog to guide a wheel when passing over the frog. In this connection the flange or rib may be made integral with 25 the frog when the frogs are manufactured or may be suitably secured to the frogs at present being used. In providing my improved flange or rib I aim to dispense with a great many accidents which have heretofore occurred by the rolling-stock being derailed at frogs or crossovers, a large percentage of the railroad accidents occurring by the rolling-stock not perfectly passing over the frog or 30 intersection of two rails.

35 The invention further aims to provide a frog or an attachment thereto which will be extremely simple, strong and durable, comparatively inexpensive to manufacture, and highly efficient for the purpose for which it is 40 used.

With the above and other objects in view, which will more readily appear as the nature of the invention is better understood, the same consists in the novel construction, combination, and arrangement of parts to be hereafter more fully described and claimed, and, referring to the drawings accompanying this application, like numerals of reference designate corresponding parts throughout the several views, in which—

Figure 1 is a perspective view of a frog constructed in accordance with my invention. Fig. 2 is a top plan view thereof, illustrating a car-wheel in the position it occupies in passing over the frog. Fig. 3 is a transverse sectional view on the line $x-x$ of Fig. 2. Fig. 4 is

a transverse sectional view of a modified form of construction.

My improved frogs or crossovers are particularly adapted for small roads, as used in connection with quarries, coal-mines, and large works, wherein cars are used which are not always maintained in a perfect condition, a great many cars being used upon which the wheels have become worn, and consequently tend to wobble when passing over a track, particularly the frogs and switches of said track. The wobbling of car-wheels often causes the wheels when passing over a frog or crossover to mount the frog and cause a derailment of the car as it moves off of the frog or crossover.

In the practice of my invention I provide a frog-plate 1, provided at one end, at the corners thereof, with recesses 2, which form seats for the ends of rails. (Not shown.) The frog-plate is formed or provided on its upper face with flanges 3 3, which extend over the inner wall of the rail-seats at the one end of the plate to the other end of said plate. 80 These flanges may be integral with the plate, as shown in Figs. 1, 2, and 3, or may be made separate from the plate and secured thereto in any desirable manner, as by screw-bolts 4, as seen in Fig. 4 of the drawings.

The frog-plate is provided centrally of its upper face with a groove extending from end to end of the plate and widening outward in a gradual taper from a point intermediate the ends of the plate to both ends of the plate. 90 There is therefore formed by this groove on the upper face of the plate, toward one end thereof, a somewhat triangular-shaped recess 5, the widening groove at the other end of the plate being divided by a frog-point 6, 95 substantially V shape in form, and thus dividing the groove at this end of the plate into two grooves 7.

The ribs 3 3 conform in outline substantially to the side walls of the central groove 100 in the plate. The frog-point is usually provided with a notch or seat 8 to receive the end of one of the frog-rails. The grooving of the plate central from end to end in the particular manner described and the provision of the upwardly-extending flanges located a short distance away from the side walls of the groove form ledges 9, on which the tread of the wheels rides as the wheels are passing over the frog, as clearly illustrated in Fig. 2 of the drawings, the flanges 3 3 safeguarding the wheel in its passage over the

frog and assuring its traveling from the rail at one end of the frog to the proper rail at the other end thereof.

What I claim, and desire to secure by Letters Patent, is—

A railway-frog, comprising a frog-plate provided centrally of its upper face with a groove extending from end to end of the plate, the said groove widening outward in a gradual taper from a point intermediate the ends of the plate to both ends, and being divided at one end by a V-shaped frog-point, the said frog-plate having notches in its up-

per face at one end forming rail-seats, and ribs on the upper face of the plate extending from one end thereof to the inner wall of the notches at the other end in unbroken form and conforming in outline to the side walls of the central groove.

In testimony whereof I affix my signature in the presence of two witnesses.

WILLIAM J. EICHER.
